UNITED STATES PATENT OFFICE.

GEORGE WETTICH AND WILLIAM PITZER, OF NEWCASTLE,
PENNSYLVANIA.

BUTCHER'S SAW.

No. 806,033.

Specification of Letters Patent.

Patented Nov. 28, 1905.

Application filed January 28, 1905. Serial No. 243,137.

To all whom it may concern:

Be it known that we, GEORGE WETTICH and WILLIAM PITZER, citizens of the United States of America, residing at Newcastle, in the county of Lawrence and State of Pennsylvania, have invented certain new and useful Improvements in Butchers' Saws, of which the following is a specification; reference being had therein to the accompanying drawings.

10 This invention relates to certain new and useful improvements in saws, and more particularly to meat-saws and saws having detachable cutting-blades.

15 The object of this invention is the provision of novel means whereby a saw-blade can be easily and quickly detached from a saw-body when it is desired and means whereby when the blade is mounted within the saw-body it can be adjusted therein.

20 Briefly described, our improved saw consists of a body portion in which a saw-blade is adapted to be mounted. To secure the saw-blade within the body portion, we slot the depending ends of the saw-body and provide the 25 one end of the saw-body with lugs which are adapted to engage in grooves formed in the end of the saw-body, adjacent to the end thereof. To secure the opposite end of the saw-blade within the saw-body, we provide a saw-30 body with a recess adjacent to its slot and provide the end of the saw-blade with a lug that is adapted to seat within said recess. A set-screw is mounted in the saw-body to engage the lug, whereby the saw-blade may be 35 more firmly clamped and held taut within the saw-body.

40 The above construction will be hereinafter more fully described and then specifically pointed out in the claims, and, referring to the drawings accompanying this application, like numerals of reference designate corresponding parts throughout the several views, in which—

Figure is a side elevation of our improved 45 saw. Fig. 2 is a top plan view of the same. Fig. 3 is a detail perspective view of one end of the saw-body. Fig. 4 is a detail perspective view of the opposite end thereof. Fig. 5 is a vertical sectional view of one end of the 50 saw-body, illustrating the adjustable feature of our improved saw; and Fig. 6 is a vertical sectional view of one end of the saw-body, illustrating a saw-blade mounted therein.

In the accompanying drawings we have

illustrated our invention as applicable to a 55 meat-saw, comprising a body portion 1, having depending ends 2 and 3, and to the depending end is secured a suitable handle 4.

The reference-numeral 5 designates a saw-blade constructed in accordance with our invention, and by referring to Figs. 4 and 5 of the drawings it will be observed that the end 6 of the saw-blade is provided with a pin having outwardly-extending ends 7 7, while the opposite end of the saw-blade is provided 60 with an enlarged portion, forming a lug 8. To secure the saw-blade within the depending ends 2 and 3 of the saw-body, we have provided the ends of the saw-body with slots 9 and 10, and upon the edge of the depending 65 end 2 of the saw-body we provide recesses 11 11, which are adapted to receive the ends 7 7 of the pin carried by the end 6 of the saw-blade. By referring to Fig. 4 of the drawings it will be observed that when the saw-blade is placed within the slot 9 the ends 7 7 70 of the pin bear within the recesses 11 11 and retain the saw-blade within the slot 9, preventing any vertical movement of the blade within the slot. The depending end 3 of the 75 saw-body adjacent to the slot 10 is provided with a recess 12, in which the lug 8 seats when the saw is mounted in the slot 10 of the saw-body.

The reference-numeral 14 designates a set-screw which is mounted in the one edge of the saw-body to engage the lug 8, carried by the saw-blade, and this set-screw is provided with an apertured head 15, whereby the set-screw can be easily rotated to adjust the saw-blade within the body portion of the saw.

On account of the construction of the saw-body it is possible to slightly spring the same when it is desired to mount the saw-blade 5 within the body portion of the saw.

After the end of the saw-blade carrying the lug 8 has been placed within the slot 10 and the lug seated within the recess 12 the opposite end of the blade is forced downwardly within the slot 9 of the depending end 2, and the instant the ends 7 7 of the pin pass into the recesses 11 11 the saw-blade will be retained within the saw-body. Should it be desired to more firmly hold the saw-blade within the saw-body, the set-screw 14 is rotated, which will force the lug 8 outwardly toward the open end of the recess 15, this operation causing the saw-blade to be held more taut and

rigid within the saw-body. By having the lug 8 formed on one side of the saw-blade the opposite side of the saw-blade has a firm even bearing on the wall of the recess 12, and the blade is thereby prevented from assuming a position at an angle to the wall of this recess under the pressure of the screw 14.

After the saw-blade has been once secured within the saw-body it will be impossible for 10 the same to become detached during the use of the saw, as the downward pressure upon the saw has a tendency to force the saw-blade farther into the slots 9 and 10 of the saw-body, consequently retaining the saw-blade 15 within the saw-body.

While we have herein illustrated the detachable saw-blade as being used in connection with a meat-saw, we desire it to be understood that other saws, such as steel saws and 20 "jig-saws," can be readily constructed in accordance with our invention.

It will be noted that various changes may be made in the details of construction without departing from the general spirit and scope 25 of the invention.

What we claim, and desire to secure by Letters Patent, is—

1. In a saw of the type described, the combination with a body portion having slots formed 30 therein, the side wall of one of said slots having a recess formed therein, of a saw-blade, a pin carried by one end of said saw-blade and adapted to engage the edges of one of said slots, a lug carried by the opposite end of said saw-blade and adapted to seat in said recess, the side of the saw opposite said lug bearing against the wall of the slot opposite 35 said recess, and means to secure said saw-

blade within said slots, substantially as described.

2. In a saw of the type described, the combination with a body portion having depending ends, said ends having slots formed therein, the wall of one of said slots having a recess formed therein, of a saw-blade, a pin carried 40 by the one end of said saw-blade and adapted to engage the edges of one of said slots, a lug carried by the opposite end of said saw-blade and adapted to seat in said recess, the side of the saw opposite said lug bearing against the wall of the slot opposite said recess, a set-screw carried by said saw-body, and adapted to bear against said lug whereby said lug can be adjusted within said recess, substantially as described and for the purpose set forth. 55

3. In a device of the type described, the combination with a saw-blade having a transversely-disposed pin at one end and having an integral lug on one side of its opposite end, of a body portion having slotted depending ends, 60 one of said ends being formed with an enlargement on one side and a recess in said enlargement adapted to receive the lug on the saw-blade, the side of the saw opposite said lug bearing against the wall of the slot opposite 65 said recess, a set-screw passing through one side of said enlarged portion alongside of the saw-blade and bearing against the inner end of said lug, substantially as described.

In testimony whereof we affix our signatures 70 in the presence of two witnesses.

GEORGE WETTICH.
WILLIAM PITZER.
